UNITED STATES PATENT OFFICE

FRANK SPILL, OF EAST RUTHERFORD, NEW JERSEY, ASSIGNOR TO THE SPILL MANUFACTURING CO., INC., OF EAST RUTHERFORD, NEW JERSEY, A CORPORATION OF NEW JERSEY

DESIGN FOR A SPECTACLE FRAME FOR EYEGLASSES

Application filed January 21, 1928. Serial No. 24,973. Term of patent 3½ years.

To all whom it may concern:

Be it known that I, FRANK SPILL, a citizen of the United States, residing at East Rutherford, county of Bergen, State of New Jersey, have invented a new, original, and ornamental Design for a Spectacle Frame for Eyeglasses, of which the following is a specification, reference being had to the accompanying drawings, forming a part thereof.

Fig. 1 is a front elevation of a spectacle frame for eye-glasses, showing my new design; and

Fig. 2 is a top plan view of the same.

I claim:

The ornamental design for a spectacle frame for eyeglasses as shown.

FRANK SPILL.
